(57) **CLAIM**

The ornamental design for a fuel-line fitting for a decorative-flame burner as shown and described herein.

DESCRIPTION

FIG. 1 is a perspective view of a fuel-line fitting for a decorative-flame burner.

FIG. 2 is a left-side view of the fuel-line fitting for a decorative-flame burner.

FIG. 3 is a right-side view of the fuel-line fitting for a decorative-flame burner.

FIG. 4 is a front view of the fuel-line fitting for a decorative-flame burner.

FIG. 5 is a back view of the fuel-line fitting for a decorative-flame burner.

FIG. 6 is a top view of the fuel-line fitting for a decorative-flame burner.

FIG. 7 is a bottom view of the fuel-line fitting for a decorative-flame burner.

FIG. 8 is another perspective view of the fuel-line fitting for a decorative-flame burner; and,

FIG. 9 is a sectional view along line 9 of FIG. 8 to clarify the shape of the design of an exterior surface of the fuel-line fitting for a decorative-flame burner.

The broken lines in the Figures represent portions of the fuel-line fitting for a decorative-flame burner that form no part of the claimed design.
